UNITED STATES PATENT OFFICE.

WILLIAM B. NORTH, OF NEW HAVEN, CONNECTICUT, ASSIGNOR TO O. B. NORTH & CO., OF SAME PLACE.

DESIGN FOR A BUCKLE.

SPECIFICATION forming part of Design No. 12,031, dated November 9, 1880.

Application filed September 11, 1880. Term of patent 7 years.

To all whom it may concern:

Be it known that I, WM. B. NORTH, of New Haven, in the county of New Haven and State of Connecticut, have invented a new Design 5 for Buckle; and I do hereby declare the following, when taken in connection with the accompanying drawings and the letters of reference marked thereon, to be a full, clear, and exact description of the same, and which said 10 drawings constitute part of this specification, and represent, in—

Figure 1, a top view; Fig. 2, a side view.

This invention relates to a design for harness-buckles; and it consists in the configuration 15 of the buckle, as shown in the accompanying illustration and herein described.

The general outline of the frame of the

buckle is that of usual construction; but on each side A of the frame there is a raised transverse projection, *a*, curved from the central 20 line toward the forward and rear ends, as seen in Fig. 2, breaking the long surface of the sides, and in highly-polished buckles giving a pleasing effect.

I claim—

The herein-described design for a buckle-frame, consisting of a raised transverse projection on the sides *a*, the surface curved therefrom toward each end, as shown in the accompanying illustration.

WM. B. NORTH.
